S. C. BROCKINGTON, OF GROTON, CONNECTICUT.

Letters Patent No. 80,590, dated August 4, 1868.

IMPROVEMENT IN LAMPS.

The Schedule referred to in these Letters Patent and making part of the same.

TO ALL WHOM IT MAY CONCERN:

Be it known that I, S. C. BROCKINGTON, of Groton, in the county of New London, and State of Connecticut, have invented a new and useful Improvement in Lamps; and I do hereby declare that the following is a full, clear, and exact description thereof, which will enable others skilled in the art to make and use the same, reference being had to the accompanying drawings, forming part of this specification, in which—

Figure 1 represents a vertical sectional view of my improved lamp.

Figure 2 is a detail vertical transverse section of the same, taken on the plane of the line x x , fig. 1.

Similar letters of reference indicate like parts.

The object of this invention is to construct a lamp for kerosene and other hydrocarbon liquids, in which the wick will always be equally far inserted in the liquid, so that thereby a steady and equal flame will always be obtained.

The object of the invention is also to provide an oil-reservoir and connections, by means of which any number of lamps can be supplied with the necessary fuel. Thus, for example, a tank, set up on the upper floor of a house, may be provided with a series of distributing-pipes, by means of which it will supply any number of lamps, set up in any part of the house.

The invention consists chiefly in arranging within a lamp-reservoir a float, which, when it rises to a certain height in the reservoir, closes a valve, thereby preventing further supply of fuel to the reservoir. The oil is thus always kept at an equal height in the lamp, and the wick is supplied with an equal quantity of fuel.

The invention also consists in the combination of a lamp, of the aforesaid construction, with the pipe and tank, in the manner hereinbefore set forth, the pipe having a stop-cock, by means of which the supply of oil can be regulated.

A, in the drawing, represents a tank, made of sheet metal, or other suitable material, of suitable size. It is intended to be set up high enough that it will supply, through a pipe or pipes, B, one or more lamp-reservoirs, C, which are arranged lower than the tank, as shown.

A strainer, a , is or may be formed in the tank, at the mouth of each pipe B, or within each pipe B.

A stop-cock, D, is arranged in each pipe B, as shown.

The oil enters the reservoir through the bottom, as shown.

In the reservoir is arranged a float, E, from which, by means of a stem, b , a small valve, c , is suspended. The float is surrounded by a perforated guard, F, as shown. The valve c fits into the pipe B, under a seat, d , formed therein, as is clearly shown in fig. 1.

When the oil flows to the reservoir, through the pipe B, it gradually, as it rises in the reservoir, raises the float E, and, when it reaches a certain height, the float will be so high as to bring the valve c against its seat, d , and will thereby automatically prevent the further supply of oil. The wick from the burner is immersed in the oil that fills the reservoir, and will, by this arrangement, be always immersed to the same depth, for, when the contents of the reservoir are but slightly reduced, the valve will be opened, to let in enough to keep up the same level.

The construction of the burner secured to the reservoir does not form part of my invention.

Having thus described my invention, I claim as new, and desire to secure by Letters Patent—

1. The self-acting valve-attachment to lamp-reservoirs, consisting of the valve c , attached to a float, E, and made and operating substantially as herein shown and described.

2. The device set forth in the foregoing clause, in combination with the perforated guard F, arranged as shown.

3. The combination of the lamp-reservoir C with the guard F, float E, and valve c , and with the pipe B, stop-cock C, and tank A, all made and operating substantially as herein shown and described.

The above specification of my invention signed by me, this 17th day of June, 1868.

S. C. BROCKINGTON.
